(57) **CLAIM**

The ornamental design for an electronic torque wrench, as shown and described.

DESCRIPTION

FIG. 1 is a perspective view of an electronic torque wrench;

FIG. 2 is a front view thereof;

FIG. 3 is a rear view thereof;

FIG. 4 is a left side view taken along line 4-4 of FIG. 2;

FIG. 5 is a right side view taken along line 5-5 of FIG. 2;

FIG. 6 is a top view thereof; and,

FIG. 7 is a bottom view thereof.

The broken lines shown on the drawings are included for the purpose of illustrating unclaimed features of the wrench and form no part of the claimed design.
